(57) **CLAIM**

(62) Division of application No. 29/867,851, filed on Nov.
10, 2022.

The ornamental design for a holder with pads or portion
thereof as shown and described.

(51) **LOC (15) Cl.** **24-02**

DESCRIPTION

(52) **U.S. Cl.**

FIG. 1 is a front-right perspective view of a holder with
pads.

USPC **D24/184**; D24/190

FIG. 2 is a rear-left perspective view of the holder with pads.

(58) **Field of Classification Search**

FIG. 3 is a top view of the holder with pads.

USPC D24/183, 184, 190–192; D29/120.1,

FIG. 4 is a bottom view of the holder with pads.

D29/121.1, 122, 121.2; D6/596–604

FIG. 5 is a front view of the holder with pads.

CPC A61F 5/0111; A61F 5/0127; A61F 13/066;

FIG. 6 is a rear view of the holder with pads.

A61F 2/6607; A61F 5/37; A47G 9/10;

FIG. 7 is a right side view of the holder with pads.

A47C 20/021; A47C 20/023; A47C

FIG. 8 is a left side view of the holder with pads; and,

(Continued)

FIG. 9 is a sectional view of the holder with pads taken along line 9-9 in FIG. 3.

The broken lines in the drawings depict portions of the holder with pads or portion thereof that form no part of the claimed design.

1 Claim, 9 Drawing Sheets

(58) Field of Classification Search

CPC .. A61G 13/121; A61G 7/075; A61G 13/1235
